(57) **CLAIM**

The ornamental design for a paint brush cleaning tool, as shown and described.

DESCRIPTION

FIG. 1 is a perspective view of a paint brush cleaning tool showing my new design.

FIG. 2 is a side elevation view thereof, the opposite side being a mirror image.

FIG. 3 is a bottom plan view thereof; and,
FIG. 4 is an end view of the right end thereof.

The broken line showing in all of the drawing figures is for illustrative purposes only and forms no part of the claimed design.
